UNITED STATES PATENT OFFICE

2,546,099

UMBRELLA

George C. Jamison, Goodyear, and Harley A. Wagg, Phoenix, Ariz.; said Jamison assignor to said Wagg

Application August 12, 1946, Serial No. 689,870

3 Claims. (Cl. 108—3)

1

The present invention relates to umbrellas, canopies and the like ornamental rooflike structures and more particularly to a rigid or permanently ventilated covering for use in opened places such as lawns, patios, gardens, beaches, decks and the like and which can be subjected to and endure all kinds of weather.

The primary object of the present invention is to provide a covering for umbrellas which will repel the light and sun rays, form a protection against rain and have ventilating characteristics for not only reducing the temperatures beneath the covering but permit the umbrella to maintain its equilibrium upon its support when subjected to ordinary gusts of wind.

Another equally important object of the invention is to form an umbrella from pressed or molded metals, wood, plastics and the like rigid materials which can be standardized and readily and economically assembled into the finished products rendering the same comparatively inexpensive in the cost of manufacture and thereby rendering the same commercially desirable.

Other objects of the invention will be in part obvious and in part pointed out as the description continues.

In the accompanying drawings:

Fig. 1 is a fragmentary top plan view of the umbrella embodying the present invention.

Fig. 2 is a side elevation of the same.

Fig. 3 is a vertical transverse sectional view taken on the line 3—3 of Fig. 1 in the direction of the arrow points.

Fig. 4 is a detail sectional view taken on the line 4—4 of Fig. 1 in the direction of arrow points.

Fig. 5 is another detail section taken on the line 5—5 of Fig. 1 in the direction of arrow points.

Fig. 6 is a detail plan view of a section of the umbrella showing a slightly modified form of the invention.

Fig. 7 is a sectional view taken on the line 7—7 of Fig. 6 in the direction of the arrow points, and

Fig. 8 is a detail sectional view showing a modified form of connection between the vanes of the umbrella and its support forming ribs.

The umbrella as herein shown is of the conventional circular type or design, but it, of course, can be of a square, rectangular, hexagon, octagon or similar configuration, or may be arranged in multiple sections and the sheets, tubes and other parts thereof are preferably made from more or less rigid material such as wood, plastics, and metals or metal alloys or a combination of such materials in laminated or molded form.

2

However, when employing wood, the same should be laminated and impregnated with a waterproofing composition, but we preferably employed a metal such as aluminum, having its outer surface, or that surface which is exposed to the sun's rays to be highly polished so as to reflect the heat therefrom. Also the vanes of the umbrella may be painted in any color or combination of colors and fringe of the same material or of cotton or leather may be attached to the outer marginal edges thereafter add to the ornamental features of the umbrella.

The supporting post 1 may be part of a lawn table, driven into the ground or attached to any other appropriate supporting base and has a socket 2 for receiving the lower end of a center handle or rod 3 of the umbrella which latter may be adjustably connected to the post 1 whereby it may be tilted and retained at various angles to its supporting base or table.

Formed with the rod 3 is an annular flange 4 upon which rests a hub member comprising a lower circular plate 5 and retained upon the rod and plate 5 by means of an adjustable and removable knob 6 is a disc 7. In the annular groove formed between the plate 5 and disc 7 rest the inner ends of its vanes 8 and permanently connected by suitable fastening elements or the rivets as shown.

These vanes 8 are fan-shaped sheets of material palmately arranged in superimposed and spaced relation having their smaller inner ends radiating from the center rod or handle 3 and their widened outer extremities secured to a tube 9. The upper row or section of vanes are each slightly bowed to give to the umbrella the desired outer contours and their outer extremities are bent around the tube 9. The lower or inner section of vanes are bent downwardly as at 10 and then bowed to correspond with the upper vanes with their outer extremities bent around the outer ends of the upper vanes whereas the vanes may be secured by spot welding to the tube 9.

Instead of spot welding the vanes to the tube 9, we may secure the same to the latter by bending or crimping the outer extremities of the lower set of vanes about the outer ends of the upper set of vanes and tube 9 in the manner as best shown in Fig. 8 of the drawings.

To retain the upper and lower set of vanes in spaced relation we preferably arrange therebetween two circular tubes 11 and 12 which are secured to the vanes by spot welding or in other ways customary in the trade.

The vanes of the upper set are arranged in staggered relation with regard to the vanes of the lower set whereby the upper vanes slightly overlap the lower vanes to exclude the sun rays and yet provide for the free circulation of air between the vanes as is best shown by the arrows in Figure 4.

The vanes may be crimped or corrugated as shown in Figs. 6 and 7 whereby the small undulations thereof extend longitudinally to the outer ends of the vanes so that water may freely flow therefrom. Instead of employing the tubes 9, 11 and 12 for connecting and retaining the vanes in spaced relation, rivets 13 may be employed. The outer extremities of these corrugated vanes 14 may be rounded as at 15 or of any other suitable ornamental design.

From the foregoing it will be understood that the inner ends of the vanes are nested and secured between the plates 5 and 7 of the hub member as shown in Fig. 5, whereby the entire covering may be removed from the handle 3 by simply removing the knob 6 and stored when not in use, thereby reducing the amount of storage space necessary. These rigidly retained vanes when made from aluminum or similar metals should have their outer surfaces highly polished to reflect back the heat from the sun's rays and obviously will not fade, rust or depreciate when exposed to all kinds of weather thereby greatly increasing the life of the umbrella over those having coverings made from fabrics.

We claim:

1. An umbrella comprising a hub, a set of fan-shaped vanes each having its smaller end connected to the hub and radiating therefrom, a second set of fan-shaped vanes disposed below and in staggered relation to the first named set, each of said second mentioned vanes having its smaller end attached to the hub, at least a pair of annular tubular members disposed between and secured to said first named and second named sets of vanes to maintain the vanes in spaced and staggered relationship whereby air may freely circulate therebetween, and an annular tubular member secured to the outer edges of said sets of vanes to secure said vanes together.

2. An umbrella comprising a hub consisting of an upper and lower plate formed with an annular groove therebetween, a set of fan-shaped vanes having their smaller ends secured in the annular groove between said plates, a second set of fan-shaped vanes disposed below and in spaced and staggered relation to the first named set and having their smaller ends secured in said annular groove, means for maintaining said vanes in spaced and staggered relation whereby air may freely circulate therebetween, and means for connecting the outer ends of said vanes together.

3. An umbrella comprising a hub, a set of fan-shaped vanes each having its smaller end connected to said hub and radiating therefrom, a second set of fan-shaped vanes disposed below and in spaced and staggered relation to said first named set, each of said vanes having its smaller end attached to said hub, annularly extending ribs extending between the said first named and second named set of vanes for maintaining said vanes in spaced and staggered relation whereby air may freely circulate therebetween, corrugations formed in each of said vanes with their undulations extending longitudinally thereof, and means for connecting the outer edges of said vanes together.

GEORGE C. JAMISON,
HARLEY A. WAGG.
